UNITED STATES PATENT OFFICE.

CHARLES EICH, OF HOBOKEN, NEW JERSEY.

AERIAL WAR-SHIP.

1,294,334.

Specification of Letters Patent.

Patented Feb. 11, 1919.

Application filed April 26, 1917. Serial No. 164,762.

To all whom it may concern:

Be it known that I, CHARLES EICH, a citizen of the United States, residing at Hoboken, in the county of Hudson and State of New Jersey, have invented certain new and useful Improvements in Aerial War-Ships; and I do declare the following to be a full, clear, and exact description of the invention, such as will enable others skilled in the art 10 to which it appertains to make and use the same.

My invention relates to that class of airships intended for offensive and defensive purposes, the principal object being to provide an airship having a longitudinal channel-shaped gangway between a pair of supporting planes for carrying guns and other armament.

In carrying out the above object, the supporting planes are positioned at substantially a dihedral angle, and another object of the invention is to minimize side sway or listing, by the provision of horizontal and vertical balancing planes secured rigidly to the rear end of the keel or gangway.

Yet another object is to provide a novel arrangement of rudders and operating means therefor.

With the foregoing general objects in view, the invention resides in the novel features of construction; and unique combinations of parts to be hereinafter fully described and claimed, the descriptive matter being supplemented by the accompanying drawings which form a part of this specification and in which:

Figure 1 is a perspective view of the improved airship;

Fig. 2 is a top plan view thereof;

Fig. 3 is a vertical transverse section;

Fig. 4 is a perspective view of portions of the two rudders and the steering means therefor;

Fig. 5 is a detail vertical section of the hinge by which said rudders are secured to the ship; and,

Figs. 6, 7, 8 and 9 are diagrammatic transverse sections on the planes of the lines 6—6, 7—7, 8—8 and 9—9 respectively of Fig. 2.

In the drawings above briefly described, the numeral 1 has reference to a longitudinally extending keel or gangway which is channel-shaped in transverse section and 55 provided in its sides 2 with portholes 3 through which guns or the like 4 may ex-

tend for firing in practically any direction, a front gun 5 being preferably mounted at the front end of the gangway at which point a searchlight 6 will also be located.

A pair of supporting planes 7 project outwardly from and extend longitudinally along the sides of the gangway 1, above the portholes 3, said planes being curved in transverse section and being located at substantially a dihedral angle. A suitable number of masts 8 rise from the gangway 1 and are preferably located fore and aft to serve as flag staffs and also as means for supporting the aerial 9 of a wireless apparatus, both masts being braced by wires 10 which extend to the planes 7 and serve also to truss the latter. A substantially horizontal balancing plane 11 is joined rigidly at its front end to the rear end of the keel or gangway 1, the upper side of said balancing plane being equipped with a vertical plane or fin 12. These two planes serve to minimize lateral tilting or listing of the ship when in use but the action thereof is augmented to a great extent by the gondolas 13 which are suspended from the gangway 1 and positioned fore and aft, said gondolas being each equipped with one or more propellers 15 and carrying the driving means therefor. It is intended that the gondolas 13 may also be employed for carrying the crew and the munitions to be fired from the guns in the gangway or to be dropped by bomb dropping devices and the like.

In some types of the ship, appropriate elevators could well be employed between the gondolas 13 and the gangway 1, but for illustrative purposes, I have shown ladders positioned in tubes 16.

For steering the craft, a horizontally disposed rudder 17 and a vertical rudder 18 are provided, the latter being carried by and movable bodily with the former which at 19 is pivotally connected to the rear end of the gangway 1 in such a manner as to permit both vertical and horizontal swinging. Cables 20 lead from the horizontal rudder 17 to a cross arm 21 on a steering post 22 located at any suitable point in the gangway or in one of the gondolas 13, said post having a hand wheel 23 by means of which it may be rotated and being hinged at 24 between said wheel and the arm 21. Rods 25 are connected to the post 22 between the hinge 24 and the wheel 23 and are provided for adjusting the rudders 17

and 18 vertically when the wheel is tilted forwardly or rearwardly as occasion may demand. Turning of wheel 23 will so move arm 21 and cables 20 as to swing the rudders horizontally.

By constructing the improved ship as or substantially as shown and described, it will be highly efficient for either offensive or defensive purposes, the positioning of the armament in the gangway 1 serving to permit the ship to attack others or defend itself, whether it is necessary to fire upwardly, downwardly, sidewise or fore and aft. It will be observed that the construction of the gangway provides ample space for the armament and gunners as well as the commanding officers. The arrangement of balancing planes and gondolas prevents listing of the machine, said gondolas carrying considerable weight and thus serving to lower the center of gravity, as does also the low positioning of the gangway 1 and the armament therein.

Since the several advantages above pointed out are probably best obtained by the general arrangement shown and described, this constitutes the preferred form of the ship. I wish it understood, however, that within the scope of the invention as claimed, numerous minor changes may be made without sacrificing the principal advantages. Although the planes 7 could well be of any appropriate construction, said planes preferably increase in width toward their rear ends and more nearly approach a horizontal position toward said ends, as shown clearly in Figs. 6, 7, 8 and 9.

I claim:

1. An aerial war ship comprising a longitudinally extending channel shaped gangway for carrying guns and other armament, said gangway being open at its top and the sides thereof having port holes through which guns and the like may extend, sup-

porting planes extending longitudinally along the sides of said gangway above said portholes and throughout the length of said gangway, and front and rear gondolas suspended from said gangway and carrying propellers and operating means therefor.

2. An airship comprising a longitudinal keel, a pair of longitudinally extending supporting planes projecting outwardly from said keel and disposed at substantially a dihedral angle, a substantially horizontal balancing plane in rear of said keel and joined rigidly thereto, a vertical balancing plane or fin rising from said horizontal plane, and rudders beneath said horizontal balancing plane.

3. An airship comprising a relatively narrow longitudinal keel, and a pair of longitudinally disposed upwardly diverging supporting planes extending outwardly from said keel, said planes being concavo-convex in transverse section with their concave sides disposed downwardly, the angle of divergence between said planes increasing toward the rear ends thereof.

4. An air ship comprising a relatively narrow longitudinal keel, and a pair of longitudinally disposed upwardly diverging supporting planes extending outwardly from said keel and of concavo-convex form in transverse section with their concave sides disposed downwardly, said planes increasing in width toward their rear ends and the angle of divergence between said planes also increasing toward said ends.

In testimony whereof I have hereunto set my hand in the presence of two subscribing witnesses.

CHARLES EICH.
